CLAIM

The ornamental design for a cocktail smoker, as shown and described.

DESCRIPTION

FIG. 1 is an exploded perspective view of the cocktail smoker;

FIG. 2 is a front view of the mesh filter of the cocktail smoker shown separately for clarity of the disclosure;

FIG. 3 is a top of the mesh filter of the cocktail smoker shown separately for clarity of the disclosure;

FIG. 4 is a bottom-view of the cocktail smoker;

FIG. 5 is a top view of the cocktail smoker shown with the top removed for clarity of the disclosure;

FIG. 6 is a front view thereof;

FIG. 7 is a side view thereof;

FIG. 8 is a cross-sectional view of the cocktail smoker taken along line 8-8 shown in FIG. 7; and,

FIG. 9 is a bottom perspective view of the cocktail smoker, shown with the top removed.

The broken lines shown portions of the cocktail smoker and form no part of the claimed design.
